DESIGN FOR A RUG

Grover C. Carter and Frank D. Rohan,
Oakland, Calif.

Application February 10, 1941, Serial No. 98,874

Term of patent 14 years

To all whom it may concern:

Be it known that we, Grover C. Carter and Frank D. Rohan, citizens of the United States, residing at Oakland, in the county of Alameda and State of California, have invented a new, original, and ornamental Design for a Rug, of which the following is a specification, reference being had to the accompanying illustration forming a part thereof.

The figure is a top plan view of a rug showing our new design.

We claim:

The ornamental design for a rug, substantially as shown.

GROVER C. CARTER.
FRANK D. ROHAN.
